(57) **CLAIM**

The ornamental design for a shoe outsole, as shown and described.

DESCRIPTION

FIG. 1 is a front perspective view of the embodiment of the present invention.

FIG. 2 is a rear perspective view of FIG. 1.

FIG. 3 is a top plan view of FIG. 1.

FIG. 4 is a bottom plan view of the embodiment shown in FIG. 1.

FIG. 5 is a left side elevation view of the embodiment shown in FIG. 1.

FIG. 6 is a right side elevation view of the embodiment shown in FIG. 1.

FIG. 7 is a front elevation view of the embodiment shown in FIG. 1; and,

FIG. 8 is a rear elevation view of the embodiment shown in FIG. 1.

No claim is made to the inner portions of the shoe outsole or the bottom surface of the shoe outsole below the dash-dot-dash boundary line. The dash-dot-dash boundary line and the disclaim break lines (in dash-dash-dash form) form no part of the claimed design and depict environmental matters. There is no claim to the opening in the rear of the shoe outsole as shown by dash-dash-dash lining.
